I W Gibbs. Albany N.Y.

(assignor to North Harrison & Chase)

Letter Patent No 394. dated July 8th 1807

— —

The schedule referred to in these Letters Patent and making part of the same

To all whom it may concern.

Be it known that S. W. Gibbs of the City & County of Albany & State of New York have invented or produced a new design for cooking stoves & do hereby declare that the following is a full & exact description of the same.

The design consists of a variety of ornaments, arranged & combined with mouldings as represented on the model, and also in the drawings which accompany this specification.

Reference to the drawings

Fig 1. Represents a birds-eye view of the stove

" 2. " a side elevation .....

" 3. " a front elevation .....

" 4. " a back elevation .....

a. " the moulding of the top plate

b. " " " oven door

c. " " " lower part of the side plate

d. " " " " " hearth plate

What I claim as my invention and desire to secure by letters patent is the arrangement of the ornaments and mouldings herein described as constituting a design for a cooking stove.
